Specification for Design.

Patented Feb. 10, 1920.

Application filed August 29, 1919. Serial No. 320,746. Term of patent 3½ years.

To all whom it may concern:

Be it known that I, NORMAN MACBETH, a subject of the King of Great Britain, and a resident of New York city, county of New York, State of New York, have invented a new, original, and ornamental Design for Lamp-Fixtures, of which the following is a specification.

My design is represented in the accompanying drawing. Figure 1 is a side elevation of the article embodying my design and Fig. 2 is a front view thereof.

I claim:

The ornamental design for a lamp fixture as shown.

In witness whereof I have hereunto set my hand at the borough of Manhattan, city and State of New York, this 15th day of August, 1919.

NORMAN MACBETH.

Witnesses:
